UNITED STATES PATENT OFFICE.

WILLIAM N. HECKETHORN, OF FAIRFIELD, IOWA.

RAILWAY-SIGNAL.

1,320,391.

Specification of Letters Patent.

Patented Nov. 4, 1919.

Application filed May 14, 1918. Serial No. 234,367.

To all whom it may concern:

Be it known that I, WILLIAM N. HECKETHORN, a citizen of the United States, residing at Fairfield, in the county of Jefferson and State of Iowa, have invented certain new and useful Improvements in Railway-Signals, of which the following is a specification.

The invention has for an object to give an improved railway signal which will be automatically operated by a train, without requiring the use of special motors and which will utilize the moving wheels of a train to repeatedly actuate an operating mechanism, whereby a sustained signal will be given while a train is approaching a given point. It is also an important aim of the invention to present a desirable construction in parts for a signal apparatus of the character indicated, and additional objects, advantages and features of invention will appear from the relation of parts, their combination and in certain features of specific construction.

In the drawings forming a part of this application,

Figure 1 is a plan view of a section of track and crossing highway with which my invention is associated,

Fig. 2 is a side elevation thereof,

Fig. 3 is a cross sectional detail of the signal device,

Fig. 4 is a similar view at right angles to Fig. 3,

Fig. 5 is a detail of one of the track actuators,

Fig. 6 is a cross section on the line 6—6 of Fig. 5,

Fig. 7 is a cross section on the line 7—7 of Fig. 5.

There is illustrated a section of track 10 crossed by a highway 11, and close beside the track and highway a signal apparatus 12 is erected, comprising a tower 13 of any suitable construction, upon the upper part of which there is mounted to rotate a shaft 14, parallel to the mean direction of the highway 11 immediately adjacent the railroad, this shaft carrying at one end a multiplicity of radial arms or blades 15 of a suitable size, or located so as to be readily observed from either direction upon the highway 11. The tower should preferably be 10 or 12 feet or more in height, and the blades 15 may each have a length of several feet. Upon the shaft 14 there are secured

two ratchet wheels such as shown at 17 in Fig. 6, having a hub mounting 18 secured upon the shaft. Rocking pawl carriers 19 are mounted upon the shaft, inclosing the ratchet wheels, and carrying spring pressed pawls 20 engaged with the ratchet wheels, whereby alternative rocking of either of the elements 19 will result in rotation of the shaft 14. The pawl carriers may be termed rocker elements, and each is provided with an arm 21, respective links 22 being connected thereto and extended downwardly and engaged with shanks 23 at the adjacent ends of two horizontal rocker shafts 24 mounted at the base of the tower, extending to within a short distance of the track 10, and located considerably below the track. Adjacent the track the shafts 24 are provided with upwardly extending arms 25 to which there are connected track rods 35, extending in opposite directions beside the track 10, and connected at their outer ends to the cranks 36 of the actuators 37 located beside the track 80 at suitable distances from the highway 11, as will be explained. One of the track rods 35, extending beneath the highway 11 is carried in a conduit 35' for its protection. The track device 37 comprises a base portion 38, in two parts, each so shaped at the inner part as to fit snugly upon one half of the rail flange 39, and having opposed flanges bolted together as at 40 to hold the device securely clamped upon the rail. 85 Through the base a suitable bearing is formed, in which a rock shaft 41 is mounted having at the inner side of the rail a striker forging 42, upon which is substantially mounted a wiper roller 43 located at about 90 the level of the tread 44 of the rail, this shaft projecting at the outer side of the base 38 and having splined thereon a hub 45, upon which a ratchet wheel 17 is keyed. The hub is formed with an annular recess 100 47 at the side next the rail, an integral lug or stud 49 extending across the recess at one side. The adjacent element of the base 38 is provided with a lug 48 projecting into the recess 47, and between this lug and the 105 lug 49 on each side there are confined springs 50, by which the hub 45 is held yieldably in one position, with the wiper roller 43 at the initial position. The springs serve to hold the roller 43 yieldably in a 110 central position movable in either direction when engaged by a car wheel flange. The

hub 45 is provided with an elongated bearing portion 51 at the outer part, upon which there rotates a pawl carrier 19, having an annular casing portion 53 circumscribing the ratchet wheel 17, the hub 45 having a flange 54 fitting within the housing portion 53 whereby the ratchet wheel and coengaging parts are inclosed. Bearing rollers may be interposed between the parts 51 and 19 if desired. Upon the pawl carrier within the casing 53 there are mounted the pawls 20 before mentioned, the springs 20' engaging the pawls being secured upon the outer part of the housing 53.

15 A bell ringing mechanism 26 is operatively associated with the shaft 14 so that upon rotation of the latter a bell 27 will be rung as an alarm. Also upon the tower a signal light 28 is provided, within a suitable 20 housing ported at 29, a shutter 30 being pivoted adjacent this opening upon a rock shaft 31 upon oscillation of which the shutter will alternately close and open the port. The shaft is provided with a broadened arm 32, 25 and extended slidably upward through the lamp housing there are lift rods 33, connected at their lower parts to the arms 21 before mentioned. Thus, oscillation of either of the arms will cause the respective rods to lift 30 the arm 32 and operate the shutter 30.

It will be seen that in operation, the ratchet wheels in the track elements 37 at opposite sides of the highway 11 being positioned to engage the pawls only under the 35 movement of the arm 42 due to engagement of the wheels of a train approaching the crossing, as a train passes the track element, each wheel as it goes by will oscillate the arm 42, producing rotary movement of the pawl 40 carrier 19, the crank arm 36 of which will then reciprocate the track rods 35 causing a rocking movement of the shaft 24 at the adjacent side, and through the pawls on the shaft 14 rotative movement of the blades 45 15 will be produced. Correspondingly, trains moving away from the crossing will not operate the devices 37, so that needless alarm will not be given. The ratchets 18 may be of the same construction as the 50 ratchet devices of the track element 36, except that the hub element thereof will not require to be engaged by any spring as in

the case of the device shown in Figs. 5, 6, and 7. By this means, a steady rotation of the blades 15 will be produced by trains approaching the crossing in either direction, without requiring the use of spring or electric motors, or other devices of a similar nature. The shutter element 30 may be of red glass, so that when the device is in operation a series of red and white flashes will be projected alternately from the signal light assuring adequate warning at night, when the blades 15 might not otherwise be observable.

What is claimed:

1. A railway signal comprising a track, a signal device, operating devices spaced longitudinally of the track for respective operation of the signal by trains approaching in opposite directions, each operating device including a sectional base including opposed elements constructed to wedge upon a rail flange and clamped together upon one rail of the track, a revoluble shaft thereon transverse to the track, a strike arm fixed on one end of the shaft closely inward of the rail, a hub element on the outer end, resilient means coengaged between the base and hub to hold the hub yieldably in initial position, a ratchet wheel fixed on the hub, a crank element revoluble on the hub, pawls thereon engaging the ratchet wheel, the ratchet wheels and pawls being oppositely arranged in the operating devices on opposite sides of the track and operative connections between the operating devices and signal.

2. A railway signal comprising a tower, a revoluble shaft thereon, a plurality of arms thereon, without the tower, a lamp housing adjacent the arms and inwardly thereof having a light port opening in a direction parallel to the shaft and within the radius of the arms, train operated means to rotate the shaft, an oscillatable shutter before the port and operative connections between the shutter and said train-operated means.

In testimony whereof I have affixed my signature in presence of two witnesses.

WILLIAM N. HECKETHORN.
